UNITED STATES PATENT OFFICE.

RINALDO CALBECK, OF PRATT, KANSAS.

TABLE-RACK.

No. 871,670.

Specification of Letters Patent.

Patented Nov. 19, 1907.

Application filed August 10, 1906. Serial No. 330,099.

To all whom it may concern:

Be it known that I, RINALDO CALBECK, a citizen of the United States, residing at Pratt, in the county of Pratt and State of 5 Kansas, have invented certain new and useful Improvements in Table-Racks, of which the following is a specification.

This invention embodies improvements in store furniture and consists essentially of a 10 novel form of rack designed to support tables in order to economize space and afford a very convenient arrangement of the same for display purposes.

For a full understanding of the invention 15 and the merits thereof and also to acquire a knowledge of the details of construction of the means for effecting the result, reference is to be had to the following description and accompanying drawings, in which:

20 Figure 1 is a perspective view of a rack embodying the invention as in use. Fig. 2 is a front elevation of a portion of the upright having an opening therein to coöperate with the supporting member on a table.

25 Fig. 3 is a vertical sectional view showing the upright partially broken away and showing the supporting member on the table in position on the upright.

Corresponding and like parts are referred 30 to in the following description and indicated in all the views of the drawings by the same reference characters.

The drawing illustrates a simple adaptation of the invention in which the rack comprises a suitable base 1 preferably mounted on casters 2 or the like, the body of the rack consisting of the vertical upright 3 projecting up from the base 1 centrally of the latter. The upright 3 is adapted to support the 40 tables which will be carried by the rack when the latter is in actual use and said upright may be of square form if preferred. Opposite sides of the upright are formed with comparatively large horizontal openings 4 somewhat elongated and each opening 4 having a downwardly and inwardly inclined opening 5 leading therefrom. The opening 5 is preferably somewhat smaller than the opening 4 and its formation provides a cam 45 portion 6. The cam portions 6 of the various openings 5 are constituted by the inclination of the outermost sides of said openings 5. Vertical slots 7 communicate with the openings 5 and are formed in the sides 55 of the upright 3 in which the openings 5 are located.

The advantages for the peculiar formation of the openings 4 and 5 with the slots 7 will be apparent from the following: A table, shown at 8, in order to mount the same upon 60 the rack, will be provided upon the under side of the shelf 9 thereof with a headed member 10. This member is secured to the shelf 9 in any substantial way and may be screwed thereinto if desired. The head of 65 the member 10 is adapted to enter one of the openings 4 at one side of the upright 3 and by downward movement of the table said head will move into the opening 5 communicating with such opening 4. The shank of 70 the member 10 will of course pass through the slot 7 and the under side of the head of said member will ride into engagement with the cam portion 6 hereinbefore described, having a sort of wedging action to hold the 75 shelf 90 in close contact with the upright 3 and rigidly secure the table to the upright.

It will of course be understood that any suitable number of the openings 4 and 5, and the slots 7, will be located at intervals at opposite sides of the upright 3 according to the size of the rack which depends upon the number of tables desired to be placed thereon. The openings 4 at one side of the upright 3 are preferably located intermediate of those 85 openings at the opposite side so that tables positioned at one side of the upright will be in a lower plane than those at the other side and the legs of the tables will not interfere with one another. 90

The tables for which the rack is particularly designed, are parlor tables of the usual type. The manner of fastening the tables to the rack admits of a compact arrangement of the latter especially advantageous for display 95 purposes, for economizing space, and for holding the tables in positions wherein dust is not likely to collect thereon.

It will be obvious that within the scope and spirit of the invention any suitable number of the uprights 3 may be employed and the other details of invention carried out satisfactorily in connection therewith. 100

Having thus described the invention, what is claimed as new is:

1. A rack for tables comprising an upright standard having a series of horizontal openings formed in opposite sides thereof, the said horizontal openings in one side alternating with those upon the opposite side, 110 downwardly extending openings leading from the base of each of the horizontal open-

ings and the outer wall of each of the downwardly extending openings being inclined to form a cam surface, the before mentioned upright being also formed with vertical slots 5 communicating with both the horizontal openings and downwardly extending openings, and table supporting members comprising heads designed to enter the downwardly extending openings and engaging the cam 10 surfaces, the alternate arrangement of the horizontal openings in the upright standard preventing the legs of the tables upon opposite sides of the standard from interfering with each other.

15 2. A rack for tables comprising an upright standard having a series of horizontal openings formed in opposite sides thereof, the said horizontal openings in one side alter-

nating with those upon the opposite side, vertical openings being provided within the 20 standard and communicating with the horizontal openings, and table supporting members carried by the tables and formed with heads designed to enter the horizontal openings to hold the tables against the standard 25 and engage the vertical openings, the alternate arrangement of the horizontal openings in the upright standard preventing the legs of the tables upon opposite sides of the standard from interfering with each other. 30

In testimony whereof I affix my signature in presence of two witnesses.

RINALDO CALBECK.
